UNITED STATES PATENT OFFICE

120,394

DESIGN FOR A SHOE OR SIMILAR ARTICLE

David Levin and Joseph W. McGee, New York,
N. Y.

Application May 3, 1939, Serial No. 84,753

Term of patent 14 years

To all whom it may concern:

Be it known that we, David Levin and Joseph W. McGee, citizens of the United States of America, residing in the city of New York, county of New York, and State of New York, have invented a new, original, and ornamental Design for a Shoe or Similar Article, of which the following is a specification, reference being had to the accompanying drawing, forming part thereof.

Fig. 1 is a side elevation of a shoe or similar article showing our new design.

Fig. 2 is a bottom perspective view of the shoe. The opposite side of the shoe presents substantially the same appearance as the side shown in Fig. 1.

We claim:

The ornamental design for a shoe or similar article, substantially as shown and described.

DAVID LEVIN.
JOSEPH W. McGEE.
